UNITED STATES PATENT OFFICE.

WILLIAM E. WOODARD, OF FOREST HILLS, NEW YORK.

LOCOMOTIVE THROTTLE MECHANISM.

Application filed April 3, 1925. Serial No. 20,456.

The primary object of my present invention is the provision of a throttle actuating mechanism which can be operated either by power or by hand as the engineer may determine.

A further object of this invention is the provision of a device of the character indicated in which the engineer will have at all times the ability, without interference, to manually close the throttle valve without it being necessary to take any action whatever with respect to the power actuating or operating means or the condition of the latter at the time of the throttle valve closing.

Another object of this invention is the provision of a device of the character indicated in which the power actuating means will open the throttle valve and will be automatically stopped in its movement when the throttle valve reaches a predetermined point in its travel.

A further object of this invention is the provision of a device of the character indicated in which it will be possible without serious difficulty to employ an improved form of single seated throttle valve the control of which will be within the power of the engineer and which will be less subject to leakage than the common form of balance valve usually employed.

In order that my invention will be better understood I will now proceed to describe the same in connection with the accompanying drawings in which I have illustrated a preferred embodiment and in which

Fig. 1 represents diagrammatically a side view of a locomotive having my improved mechanism applied thereto.

Fig. 2 is a side elevation of the throttle lever mechanism with the latch wheel and connection shown and indicating in elevation also the power motor which, in this case, is shown as a fluid actuated rotary engine supported on the casting or bracket which carries the throttle lever.

Fig. 3 is another side view of the throttle lever showing the latch wheel and worm gear which I employ and certain of the related parts.

Fig. 4 is a detailed view showing certain of the parts by which control is exercised over the power device.

Fig. 5 is another detailed view showing

another position of the parts as indicated in Fig. 4.

Fig. 6 is a view partly in section showing the improved form of throttle valve which I use in my invention, and

Fig. 7 is a sectional view of the valve which I use to control the operation of the power motor.

Referring now more particularly to Fig. 1 it will be seen that I have therein indicated a diagrammatic view of a locomotive having a boiler 1 at the forward end of which the shell of the boiler is cut away so as to disclose the steam pipe 2 which in this arrangement extends from the superheater header 3 to the throttle valve casing 4, the outlet from the latter being by the pipe 5 which extends downwardly to connect with the steam chest 6.

On the boiler head of the locomotive at the rear, I mount a supporting casting 7 which carries the power motor 8 and the throttle lever 9, the latter being in turn connected by a rod 10 with a rocking lever 11, the other end of which is in turn connected by the rod 12 with the rocker shaft lever 13 at the forward end of the locomotive which actuates the throttle valve proper.

Air for the actuation of the motor 8 is supplied preferably thru the pipe 14 from the main reservoir 15 or some other suitable source of fluid pressure supply and is subject to control by a valve 16 which latter is subject to operation by means of the connections 17 and 18, the bell crank lever 19 and the short lever 20 on the outer end of its throttle lever which latter is actuated by partial rotation of the button 21.

The throttle lever 9 is shown in Fig. 1 in forward position, that is with the throttle closed and the opening of the throttle is to be accomplished as is usual in connection with throttle actuating mechanism on locomotives by a backward movement of the throttle lever.

In the mechanism constituting an embodiment of my improvement as shown in the drawings herewith, the lever 9 may be operated either by hand or release of the latch device 22 which establishes connection with the latch wheel 23 or it may be actuated to open the throttle by rotation of the latch wheel 23 carrying the lever 9 along with it

when the latch is in engagement with the wheel 23, such rotation being obtained through the action of the motor 8 under the air pressure admitted through the valve 16 by partial rotation of the button 21.

From examination of Fig. 3 it will be seen that when the shaft of the motor which carries a worm 24 is caused to revolve, this will rotate the worm gear 25 which latter is fast to the shaft 26 and will cause a rotative movement of the latch wheel 23 and this with the latch 22^a in engagement as shown in Fig. 3 will cause a movement of the throttle lever 9 toward the left as indicated by the arrow marked "Open" in Fig. 2.

The pull transmitted through the rod 10, rocking lever 11 and rod 12 serves to rock the rocker shaft arm 13 to the right as indicated in Fig. 6 which in turn raises the pilot valve 27 allowing first a small amount of pressure to pass downward through the main throttle valve 28 and then by the engagement of the collar 29 with the lower face of the main throttle valve 28 serves to raise the latter and admit steam to the cylinders of the locomotive in quantities as desired.

It will be seen from study of Fig. 6 that I have therein shown a single seated throttle valve having a relief or pilot valve 27 mounted in its center and guided preferably by the wings 30 and the stem 31 which latter carries the collar or shoulder 29 functioning as described.

Fig. 7 is a sectional view through the control valve 16 which governs the admission and exhaust of pressure to the motor 8. This device has a valve stem 32 carrying an inlet valve 33 on one end and an exhaust valve 34 at the other end and held by a spring 35 in position to keep the exhaust valve normally open and the inlet valve 33 normally closed, the spring being arranged so that it will be overcome when it is desired to open the valve 33 and close the valve 34 by pressure on the stem 36 derived from the lever 37 through action of the rod connection 17 that leads through the bell crank lever 19 and connection 18 to the lever 20 and button 21 which last is the specific means whereby the engineer actuates the valve 16 so as to control the operation of the power motor 8.

From the above it will be obvious that when the engineer desires to use the power motor for opening the throttle valve he rotates the button 21 admitting air to revolve the motor 8 by the control valve 16 and the revolution of the motor 8 with its connected worm 24 turns the associated worm gear 25 which in turn revolves the shaft 26 and the latch wheel 23 and the latter through the latch 22^a mounted on the throttle lever 9 carries the throttle lever along to the left in Fig. 1 and Fig. 2,

this manipulation opening the throttle valve 28 to supply steam to the cylinders.

The opening movement of the throttle lever 9 can be stopped at any predetermined point by the engineer by merely reversing the movement of the button 21 and shutting off the air supply to the motor 8 which will stop revolving and the throttle lever 9 will stand in the stopped position whatever it may be because of the presence and resistance of the worm 24 to any backward or other movement of the connected worm gear.

If the engineer desires to have the throttle valve automatically opened wide all that is necessary is for him to start the action by rotating the button 21 and then allow it to travel full distance at which time the stop screw 38 which, as shown, is adjustable within the bracket 39, will come in contact with the lever shown in dotted lines at 40 after which further movement of the throttle lever 9 will push on the rod 17 and shut off the air supply to the motor automatically. Fig. 4 shows these parts just at the time when the automatic screw stop begins to take effect and Fig. 5 indicates a slight movement of the parts in the direction of closing the control valve thru the rod 17.

It is one absolute requirement of any locomotive throttle valve that it may be instantly closed with a minimum amount of effort on the part of the engineman or else the device is not safe to use. In order to provide for this, it will be observed that pressure on the latch 22 will immediately release the latch wheel 23 by withdrawal of the toothed member 22^a from engagement with the latch wheel teeth and regardless of what position may be assumed by the parts which are connected with the motor 8 and the control valve 16, the engineer can manually push the throttle lever 9 toward the boiler head, that is, forward and effectively close the throttle.

In the preferred arrangement of my improvement as shown I use a throttle valve which is placed between the locomotive superheater and the cylinder and actuates said throttle valve through the medium of a power throttle device situated in the cab. It is obvious, however, that other and somewhat different arrangement of these parts might be introduced without departing from the spirit of my invention.

The importance of my improvement will be obvious from consideration of the fact that there is an increasing burden placed upon the engineer in the actuation by hand of the throttle devices because of the large increase in size and power and the higher pressures of steam used in modern types of locomotives.

The form of throttle most commonly used, known generally in the art as a balance valve, has two seats with rigid connection be-

5 between both in the valve and the valve casing as the result of which it is a matter of considerable difficulty to make these valves tight. On the other hand to regularly use such a detailed form of valve as I have herein shown or any single seated valve with the present size of locomotive and steam pressures generally employed requires such strength and effort on the part of the engineer as to become very burdensome. At 10 the same time in connection with the improvement which I have herein disclosed I have shown apparatus in which if, for any reason, it is necessary or desirable to manipulate the apparatus entirely by hand, that 15 can be done with directness and safety.

Reversing fluid pressure motors can be used if desired and the throttle lever partially or wholly closed by fluid pressure, at 20 the same time preserving the possibility of hand operation as before.

I claim:—

1. A locomotive throttle mechanism comprising in combination a throttle valve, power operating means for said throttle valve, such means being under the control of the engineman, means for engaging and disengaging the throttle valve operating mechanism from the power means at will, and 25 means for automatically stopping the throttle opening at a predetermined point.

2. A throttle operating mechanism for locomotives comprising a single seated throttle valve, a hand actuated mechanism 30 with a lever in the cab for opening and closing said throttle valve, motor means for actuating said hand operating mechanism and means for engaging and disengaging the power means at will, said throttle lever hav-

ing connection with the power actuating 40 means by latch engagement, said latch engagement and power actuating connections being carried by the throttle lever shaft.

3. A locomotive throttle operating mechanism comprising, in combination, a throttle 45 valve, power operating means for said throttle valve, hand operating means for said throttle valve having a lever in the cab, and means on said lever for engaging and disengaging said power operating means at 50 will.

4. A locomotive throttle mechanism comprising, in combination, a single seated 55 throttle valve, hand actuated means with a lever in the cab for opening and closing said throttle valve, motor means for actuating said hand operating means, and means on said lever for engaging and disengaging the power means at will.

5. A locomotive throttle operating mechanism comprising, in combination, a throttle 60 valve, power operating means for said throttle valve, hand operating means for said throttle valve having a lever in the cab, and means on said lever for engaging and disengaging said power operating means at will, 65 together with means also on said lever for controlling the power operating means.

6. A locomotive throttle operating mechanism comprising, in combination, operating 70 means for the throttle having a hand lever, power actuating means for said operating means, and means on said lever for engaging and disengaging said power means.

In testimony whereof, I have hereunto 75 signed my name.

WILLIAM E. WOODARD.
